The ornamental design for a POP-UP POWER UNIT as shown and described.

DESCRIPTION

A description of each of the figures of the drawings is as follows:

FIG. 1 is a perspective view of a pop-up power unit in a retracted position.

FIG. 2 is a first side view of the pop-up power unit in the retracted position of FIG. 1.

FIG. 3 is a second side view of the pop-up power unit in the retracted position of FIG. 1.

FIG. 4 is a third side view of the pop-up power unit in the retracted position of FIG. 1.

FIG. 5 is a fourth side view of the pop-up power unit in the retracted position of FIG. 1.

FIG. 6 is a top view of the pop-up power unit in the retracted position of FIG. 1.

FIG. 7 is a bottom view of the pop-up power unit in the retracted position of FIG. 1.

FIG. 8 is a perspective view of a pop-up power unit in an extended position.

FIG. 9 is a first side view of the pop-up power unit in the extended position of FIG. 8.

FIG. 10 is a second side view of the pop-up power unit in the extended position of FIG. 8.

FIG. 11 is a third side view of the pop-up power unit in the extended position of FIG. 8.

FIG. 12 is a fourth side view of the pop-up power unit in the extended position of FIG. 8.

FIG. 13 is a top view of the pop-up power unit in the extended position of FIG. 8.
